DESK

John J. Hughes, Jr., Milwaukee, Wis., assignor to Invincible Metal Furniture Company, Manitowoc, Wis., a corporation of Wisconsin

Filed Oct. 20, 1964, Ser. No. 82,247

Term of patent 14 years

(Cl. D33—7)

FIG. 1 is a perspective view of a desk showing my new design;

FIG. 2 is a rear perspective view thereof;

FIG. 3 is an enlarged fragmentary detail view partially in perspective and partially in section on the line 3—3 of FIG. 1.

FIG. 4 is an enlarged fragmentary detail view partially in perspective and partially in section on the line 4—4 of FIG. 2.

The desk is characterized by a pair of contrastingly colored channel members recessed immediately beneath the top and extending longitudinally the full distance between the leg supports, all as shown.

I claim:

The ornamental design for a desk, as shown and described.
